BRUNO ROSENBAUM, OF BERLIN, GERMANY, ASSIGNOR TO WESTINGHOUSE ELECTRIC & MANUFACTURING COMPANY, A CORPORATION OF PENNSYLVANIA.

ARRANGEMENT FOR PRODUCING OSCILLATIONS BY MEANS OF VACUUM TUBES.

Application filed October 31, 1921, Serial No. 511,773, and in Germany January 22, 1921.

This invention relates to oscillation generators of the vacuum-tube type.

It is an object of this invention to provide a means by which a source of direct current may be made to sustain a continuous high-frequency oscillation.

More specifically stated, the object of this invention is to provide a vacuum-tube path for the current in shunt with the main vacuum-tube path and to vary the distribution of the current between the two paths at the period of the oscillations.

Other objects of the invention and specific details of the construction will become evident from the following specification and the accompanying drawing, in which—

Figure 1 is a diagram of a form of the device using one vacuum tube.

Fig. 2 is a diagram of a modification in which two vacuum tubes are used.

Fig. 3 is a diagram of a further modification in which the changes in the electron path are controlled by a magnet, and

Fig. 4 shows a further modification in which the arc is intermittent.

The tube shown in Fig. 1 may be a gas-free vacuum tube or a mercury-arc tube. The cathode 2 is illustrated as heated by the battery 3 through the adjustable resistance 4, but any other form of hot cathode, such as the surface of a pool of mercury, may be used. The tube is supplied with two anodes providing two divergent space-current paths. The external circuit connected to the anode 6 includes a condenser 7, having an inductor 19 shunted about it. The resonant circuit, comprising the condenser and inductor, is connected to one pole of a direct-current source 8. The other pole of this source is connected to the cathode 2. Between the two poles of the source 8, is a condenser 9 which affords passage for the high-frequency current. The positive pole of the source 8 is also connected to the anode 5 and the negative pole is connected to the grid or supplemental electrode 10. This connection to the grid includes a coil 11 inductively related to the coil 19 in the oscillating circuit.

In the operation of this device, the space current between the cathode 2 and the anode 6 charges the condenser 7 and, when

this condenser reaches its maximum potential, the counter-electromotive force of it checks the space current to the anode 6. 55 The relation of the direction of the windings of the coils 11 and 19 is such that, at the time the counter-electromotive force of the condenser is checking the space current, the potential impressed upon the grid 10 by 60 the electromotive force induced in the coil 11 is of a sign that assists the flow of space current between the cathode 2 and the anode 5. The diminution of the space current to the anode 6 is, therefore, accompanied by an 65 increase in the space current to the anode 5. As the electron emission from the cathode 2 is virtually constant, increase of the current in one path is necessarily accompanied by a decrease of current in the other path. If 70 the tube 1 contains gas, such as mercury vapor, the limit of the total current is fixed by the ionization, so that it is still true that increase in the current to the anode 5 is 75 accompanied by a decrease of current to the anode 6. It is, therefore, apparent that the changes, due to the variations of the charge upon the condenser 7, set up oscillations. The period of these oscillations is fixed by the constants of the circuit comprising the 80 condenser 7 and the indicator 19. Thus, the energy derived from the direct-current source 8 gives rise to sustained oscillations in the oscillating circuit. The inductor 19 may be used to supply energy to an antenna 85 or to any other working circuit; also the connection to the anode 5 may contain any working or absorbing circuit that is desired.

In the form illustrated in Fig. 2, the 90 source 8 is supplied with an adjustable resistance 17 and there are two choke coils 12 and 14 between the source and the condenser 9. The connection from the positive side of the source goes to two anodes, but, in this form, these anodes are in separate tubes 15 and 16. Each of these tubes is provided with a cathode heated by its own battery, and the two cathodes are connected to the negative side of the source. The connection to the anode of the tube 16 includes a condenser 7 and an inductor 19, as in the form illustrated in Fig. 1. The coil 11, in inductive relation to the coil 19,

applies a varying potential to the grid of the tube 15. The grid of the tube 16 is provided with any grid biasing device. Preferably, this device is made adjustable.

- 5 The operation of this form of the device is closely similar to that described in connection with Fig. 1. Oscillations are set up in the circuit including the condenser 7 and the inductor 19. These cause fluctuations upon the grid of the tube 15, through the coupling between coils 11 and 19. The relation of the windings of these two coils is such that, when the current through the tube 16 is diminishing, the charge upon 10 the grid in the tube 15 is of a sign to cause the current through the tube 15 to increase. The constant character of the source 8, together with the steadyng effect of the choke coils 12 and 14 and the condenser 9, causes 15 the increase in the current through the tube 15 to be accompanied by a further decrease in the current through the tube 16. Consequently, once oscillations are started, they tend to build up to a maximum.
- 20 25 In the form shown in Fig. 3, the source 8 is connected, as already described, to two vacuum-tube devices; one of which 16 is like the tube 16 in Fig. 2. The grid biasing means in this figure has, however, 30 been shown as an adjustable "C" battery. The second tube 25 is here shown as a mercury-arc device including a liquid mercury cathode 26 and two anodes 27 and 28. The anode 28 is connected to the positive 35 side of the source 8 through a resistance 29 which is of such a size that current to the anode 28 will be just sufficient to maintain the arc. The secondary 11 is connected to an electromagnet 30 in a position to influence the arc. The direction of the windings in coils 11 and 19 and in the magnet 30 is such that, when current through the tube 16 is diminishing, the magnet will 40 cause the arc to go to the anode 27, instead 45 of the anode 28. This will cause an increase in the current through the tube 25, because the path through anode 27 avoids the resistance 29. Upon increase of current 50 through the tube 16, the magnet 30 will cause the arc to return to anode 28. The resistance 29 then causes current through the tube 25 to decrease, thus adding to the increase through tube 16. Accordingly, oscillations once started will be sustained by 55 the action of the tube connected in shunt to the tube 16.

In the form shown in Fig. 4, similar connections are provided, except that the tube 25 contains but one anode 27. When the 60 current through the tube 16 is maximum it shunts the tube 25 sufficiently to cause the arc to extinguish. The secondary 11, when the current through the tube 16 begins to diminish, applies a potential to the grid of the supplemental tube 31 of a sign which

causes the current of this tube to increase and it increases to such a point that a spark passes between a terminal 32 within the tube 25 and the cathode 26. This spark sets up ionization and so starts the tube 25 to conducting again. Flow of current through the tube 25 shunts the tube 16 and thus causes further diminution in the current through this tube. Thus, oscillations once started in the circuit including condenser 7 and the 75 inductor 19, the action of the shunted tube makes the oscillations build up.

It will be obvious that many variations of the specific construction employed can be used without departing from the spirit of 80 this invention, I, therefore, do not propose to limit it except as necessitated by the prior art or indicated by the claims.

I claim as my invention:

1. In an oscillation generator, a main circuit, a shunt, each including a space-current path, a common source supplying said main circuit and shunt with current, a grid in the space-current path of said shunt, means energized by current changes in said main circuit for varying the potential of said grid and thereby varying the impedance of said shunt, whereby the current changes in said main circuit are amplified, said amplification being effected wholly by said variations in the impedance of said shunt.

2. In an oscillation generator, a main circuit, a shunt, each including a space-current path, a common source supplying said main circuit and shunt with approximately constant current, means associated with the space-current path of the shunt and energized by current changes in said main circuit for varying the impedance of said shunt, whereby the current changes in said main circuit are amplified, said amplification being effected wholly by said variations in the impedance of said shunt.

3. In an oscillation generator, a main space-current device, a tuned circuit energized through said main space-current device, means associated with the shunt space-current device, for altering the impedance thereof and means, energized from said tuned circuit, for controlling said impedance altering means, the impedance of said main space-current device being independent of the oscillations in said tuned circuit.

4. In an oscillation generator, a source of approximately constant direct current, two parallel circuits supplied therefrom, a space-current device in each of said circuits, means, including a grid, for controlling the impedance of one of said space-current devices and means for impressing a varying potential on said grid whereby the current through but not the impedance of the other of said space-current devices is changed at the frequency of said varying potential.

5. In combination, two vacuum-tube de-

vices, each having a grid, means for maintaining one of said grids at a constant potential, means for impressing on the other grid a potential varying in accord with the last-named vacuum-tube device in accord with the changes in the impedance of the vacuum-tube device having a varying grid 10 potential.

5 current changes through the vacuum-tube device having constant grid potential, and means for changing the current through the

In testimony whereof I affix my signature.

BRUNO ROSENBAUM.
